UNITED STATES PATENT OFFICE.

WILLIAM H. A. DAVIDSON, OF CAMBRIDGE, MASSACHUSETTS.

VENTILATING WHEEL OR FAN.

SPECIFICATION forming part of Letters Patent No. 598,216, dated February 1, 1898.

Application filed July 1, 1895. Serial No. 554,624. (No model.)

To all whom it may concern:

Be it known that I, WILLIAM H. A. DAVIDSON, a citizen of the United States, and a resident of the city of Cambridge, in the county 5 of Middlesex and State of Massachusetts, have invented certain new and useful Improvements in Ventilating Wheels or Fans, of which the following is a specification.

Heretofore ventilating wheels or fans have 10 been constructed with blades of divers shapes set radially and at an angle to and across the axis of the shaft which constituted their center of rotation. In such fans only the forward or cutting edge of the blade was effective to gather in the air, while the configuration of the blade-surface tended to disperse the volume of air passed through the fan in directions at various angles to the axis of rotation of the fan, and where the air was to be 15 forced through ducts or confined channels placed in the rear of the fan such diverging currents tended to create friction and resistance to the effective work of the fan.

I have in practical tests of my invention 20 demonstrated that greater volume of air can be moved or given direction through the fan by setting and arranging the blades in the fan or wheel in the manner shown in the accompanying drawings and more fully described hereinafter, and that such construction presents much less obstruction to the free movement of the currents of air generated by the wheel or fan in motion. I have further 25 demonstrated that blades in the form of a segment of a prolate spheroid when arranged in the fan as last above stated are better and more efficiently adapted to concentrate and deliver the current of air through the fan in right lines, or nearly so, parallel with the axis 30 of the fan, and with a minimum of frictional resistance where the air is to be forced through ducts.

I have secured the best results by constructing the blade in the form of a segment of a 35 prolate spheroid or in the form of a spoon-bowl, from which its extreme ends have been cut off in such manner as to provide a blade with an inner concave face and an outer convex face and by arranging such blades in the 40 wheel or fan in manner following: I first secure upon the shaft or hub spokes, each of which projects from said shaft with its lon-

gitudinal axis at the point of junction with the shaft or hub, eccentric to the axis of the latter. Upon each said spoke I secure, preferably adjustably, an arm which projects from the rear side of said spoke with reference to the direction of rotation. Upon said rearward-projecting arms I secure blades of the character above described, with their surfaces at approximately right angles to the longitudinal axis of said spokes and angularly inclined to the vertical plane of the axis of rotation. Said blades are arranged to extend forward of the spokes and are set with their 60 cutting edges nearest the periphery of the wheel and their delivery edges nearest the center of the wheel.

The fan is mounted in a frame or bearings and driven in the ordinary way. It may be 65 used in connection with an air-duct or not, as may be desired.

Within considerable limits the outline of the edges of the blade may be varied, (I have shown two variations,) provided the essential 70 curvatures, such as are found in a spoon-bowl, are retained.

In the accompanying drawings, illustrating my invention, Figure 1 is a front elevation of a fan embodying my invention. Fig. 2 is a 80 side elevation of the same. Fig. 3 is a rear view of the same, looking in the direction of the arrows from line $x\ x$ of Fig. 2. Figs. 4 and 9 show the mode of attaching and securing the blade, a portion of the blade being 85 broken away and the arm and clamping-nut being shown in section. Fig. 5 shows a plan, a side, and a sectional view of the split clamping-nut. Figs. 6, 7, and 8 are respectively front, side, and rear views, differing from Figs. 90 1, 2, and 3 only in the shape of the outer edge of the blades. Fig. 10 is a section on line $z\ z$ of Fig. 9.

Similar letters of reference indicate like parts where they occur in the drawings.

A represents the blade, which may, as shown in Figs. 1, 2, 3, and 4, have the spoon-shaped outline, or, as shown in Figs. 6, 7, 8, and 9, while still preserving the curvatures of a spoon-bowl, may at the same time have its 100 opposite sides or edges more nearly parallel, and in either case is provided with a stem or shank or secured upon an arm a , the lower end of which is threaded and adapted to

be engaged by an internally-threaded split clamp-nut *n*, provided with rectangular tapered sides adapted to fit into the correspondingly-tapered rectangular orifice in the spoke 5 *b* and to be drawn thereinto bindingly by the action of the check-nut *c* against the under side of said spoke *b*, to rigidly secure the blade in position with its surfaces at approximately forty-five degrees to and at the longitudinal axis of the arm and angularly inclined to the vertical plane of the axis of the fan. The spokes *b* are located upon the side of the hub or shaft of a wheel or fan eccentrically to the axis of the same and extend 10 outward in a radial direction from said hub or shaft. The spokes *b* may, if desired, form an integral part of the hub or shaft. The shaft *s* may be mounted on bearings or in a frame in the usual way and operated in 15 the ordinary manner. The blade may be adjusted at any desired angle to the axis of the shaft and thereby adapted to varying conditions and exigencies of work.

I claim as my invention and desire to set 25 cure by Letters Patent—

1. The combination with the fan-shaft of spokes projecting therefrom, substantially spoon-shaped blades secured to arms projecting from the rear side of said spokes with 30 reference to the direction of rotation, with their surfaces at approximately right angles to the longitudinal axis of the spokes and inclined to the vertical plane of the axis of rotation, the said blades extending forward 35 of the spokes and so set that their cutting edges are nearest the periphery and their delivery edges nearest the center of the wheel.

2. In a ventilating wheel or fan spokes located on the side of the shaft of rotation and 40 projecting in a radial direction therefrom with the longitudinal axis of said spokes at their junction with said shaft eccentric to the axis of the latter, arms adjustably secured upon said spokes and projecting from the rear side 45 thereof with reference to the direction of rotation, and substantially spoon-shaped blades secured to said arms and extending forward of said spokes with their surfaces at approximately right angles to the longitudinal axis 50 of said spokes and angularly inclined to the

vertical plane of the axis of rotation and so set that their cutting edges are nearest the periphery and their delivery edges nearest the center of the wheel.

3. In a ventilating wheel or fan spokes *b* 55 each located upon the side of the shaft of rotation and projecting in a radial direction therefrom with their longitudinal axis at the point of junction with said shaft eccentric to the axis of the latter, combined with blades 60 arranged upon the rear side of said spokes with reference to the direction of rotation, with their surfaces at approximately right angles to the longitudinal axis of said spokes and inclined to the vertical plane of the axis 65 of rotation, the said blades extending forward of the spokes and so set that their cutting edges are nearest the periphery and their delivery edges nearest the center of the wheel.

4. The combination with a shaft and hub, 70 of spokes *b* secured on the side of said hub and projecting in a radial direction therefrom, with the longitudinal axis of said spokes at the point of union with the hub eccentric to the axis of the latter, and blades *A* adjustably secured and centrally supported upon the rear side of said spokes with reference to the direction of rotation with their surfaces at approximately right angles to the longitudinal axis of the spokes and inclined to the 80 vertical plane of the axis of rotation, the said blades extending forward of the spokes and so set that their cutting edges are nearest the periphery and their delivery edges nearest the center of the wheel. 85

5. In a ventilating wheel or fan, the blades *A* provided with a threaded stem or shank, the annular split clamping-nut *c* and check-nut *n*, all combined with each other and with the spokes *b* provided with a rectangular-tapered orifice, and arranged and adapted to 90 serve as specified.

In testimony whereof I have hereunto set my hand, in presence of two witnesses, this 29th day of June, 1895.

WILLIAM H. A. DAVIDSON.
